UNITED STATES PATENT OFFICE.

OTTO S. BEYER, OF BROOKLYN, NEW YORK, ASSIGNOR TO E. W. BLISS COMPANY, OF BROOKLYN, NEW YORK, A CORPORATION OF WEST VIRGINIA.

DRAWING PRESS.

Application filed June 30, 1922. Serial No. 571,952.

To all whom it may concern:

Be it known that I, OTTO S. BEYER, a citizen of the United States, residing at No. 221 Eighth Avenue, in the borough of Brooklyn, city and State of New York, have invented certain new and useful Improvements in Drawing Presses, of which the following is a specification.

This invention relates to drawing presses, and aims to provide improvements therein.

The present invention provides an improved drawing press which is peculiarly suitable for making large stampings, and in which the distance between uprights is considerable.

The invention further provides a construction wherein parts of the blank-holder or die-carrying slide actuating mechanism may act to counterweight said slide.

The invention further provides novel combinations and subcombinations of parts for effecting the functions of a drawing press of the type referred to.

Two embodiments of the invention are illustrated in the accompanying drawings, in which,—

Figure 1 is a view in elevation, (with certain parts shown in section on one side of the midplane of the figure,) showing one embodiment of the invention.

Fig. 2 is a view in elevation of the parts at one side of the press, showing these parts in the opposite extreme position to that shown in Fig. 1.

Fig. 3 is a side view of parts shown in Fig. 2, at the left of the line 3—3, Fig. 2.

Fig. 4 is a detached perspective view of certain of the rock shafts and their connecting parts shown in Figs. 1 and 2.

Fig. 5 is a view showing a modified arrangement of the rock shafts and their connecting parts, shown in Fig. 4.

Fig. 6 is a view in elevation of a second embodiment of the invention, only one-half of the press being shown, the other half being an enantiomorphic duplication of the parts shown.

Fig. 7 is a view in side elevation of the press shown in Fig. 6, the wheel at the left of the line 7—7 being omitted.

Referring to said drawings, numeral 10 designates the frame of the press, comprising the side frames or uprights 11, 11, which, in presses for large stampings, are spaced a considerable distance apart. These side

frames are usually narrow as compared with the distance across the press between uprights.

15 designates a slide, which is adapted to carry a blank-holder or die, according to the direction of action of the punch, and adapted to coat with a complementary blank-holder or die, as the case may be, on the bed 20 of the press.

25 designates a punch slide (adapted to carry a punch), and, in its preferred form, as here shown, sliding upon the blank-holder or die-carrying slide 15, as indicated at 26. The punch slide 25 is conveniently actuated by a crank-shaft 28, usually through a plurality of cranks 29 and connecting rods 30.

Means are provided for reciprocating the blank-holder or die-carrying slide 15 toward and from the bed 20, in such manner that the said slide 15 dwells during the action of the punch. During this dwell the tools on the slide 15 and bed 20 engage or grip the marginal portion of a blank which is being shaped by the punch.

These means for reciprocating the slide 15 comprise a plurality of rocking parts 35, which are conveniently in the form of rock shafts having toggle connections 37 to the blank-holder or die-carrying slide 15.

As shown in Figs. 1 to 5, inclusive, the rocking parts 35 are arranged on an axis running from front to rear of the press, that is, transverse of the side frames 11, and at right angles to the axis of the crank shaft 28. A rocking part is preferably provided at the front and rear of the press, at each side of the press, providing four points of connection or support of the slide 15 to the press frame. A single rock shaft 39, running from front to rear of the press, conveniently forms a pair of rocking parts at each side of the frame. Each of the rocking parts 35 comprises an arm 41, which, together with a link 42, form each of the toggles 37. An arm or arms 43 is also provided for transmitting motion to the rocking parts 35. As shown in Figs. 1, 2 and 4, these arms 43 are conveniently formed integral with the arms 41, while, as shown in Fig. 5, the arms 43 may be consolidated into a single arm 43' and attached to an intermediate part of the rock shaft 39. The rocking parts 35 are conveniently actuated by a reciprocating slide or the like 45, through intermediate parts comprising a sec-

100

105

110

ond rocking part or parts 50. The rocking part or parts 50 are conveniently in the form of a rock shaft 51 on an axis parallel to the axes of the rocking parts 35. As shown in 5 Fig. 4, there is one rocking part 50 for each of the rocking parts 35, while in Fig. 5 a single rocking part 50', acting through the arm 48', acts to turn each of the rocking parts 35 through the rock shaft 39. For 10 this purpose the rocking parts 50 may be connected to the rocking parts 35 through arms 53 and links 54, these arms and links 53 and 54 constituting toggles 55 preferably arranged so as to straighten simultaneously 15 with the toggles 37. The rocking parts 50, when in the form shown in Figs. 4 and 5, may be provided with a single arm 57, attached to the rock shaft 51, receiving motion from the slide 45 through a link 58.

20 The reciprocating slide 45 is actuated by a rotary part 60 having a cam or eccentric groove 62 therein. The slide 45 has a part 63 adapted to fit within this groove, which part 63 is conveniently in the form of a 25 slide block having a broad bearing surface on the walls of the groove 62, as indicated at 65.

The rotary part 60 is conveniently in the 30 form of a gear wheel on an end of the crank shaft 28, at each side of the press, the gear wheels 60 being driven in any convenient manner, as by pinions, on a back shaft 67, and thereby serving to transmit motion to the ends of the crank shaft 28, as well as to 35 the slides 48 which actuate the pairs of rocking parts 35 at each side of the press.

The slides 45 conveniently move in slide-ways 70 between the side frames and the inner faces of the gear wheels 60, the cam or 40 eccentric groove 62 being formed on the inner faces of said wheels 60.

The slide 45, and the axes of the rocking parts 35 and 50, being arranged close to the side frames of the press, provide a short, 45 compact and powerful transmission from the rotary parts 60 to the blank-holder or die-carrying slide 15. This arrangement also relieves the crown 75 of the press of severe strains, these being largely sustained by the 50 side frames 11 and their reinforcing parts.

In the embodiment shown in Figs. 6 and 7 the construction is similar to that shown in Figs. 1 to 5, inclusive, with the exception that the rocking parts 35 are arranged to 55 turn on axes running from side to side of the press, that is, parallel to the axis of the crank shaft 28. In this construction the rocking parts at front and rear of the press, on opposite sides, may be made in pairs in 60 the form of a single rock shaft 80 extending from side to side of the press. These rocking parts 35 may be provided with arms 43', which are directly connected to the slide 45' by means of links 82. The construction 65 and operation of the embodiment shown in

Figs. 6 and 7 are otherwise the same as that of the first embodiment.

The inventive ideas herein set forth may receive other embodiments than those herein specifically illustrated and described. 70

What I claim is:—

1. A drawing press comprising a blank-holder or die-carrying slide and means for reciprocating the same with a dwell in its movement, said means comprising two rocking parts at the same side of the press, and means comprising a rotary cam on the same side of the press as said rocking parts for simultaneously rocking said rocking parts. 75

2. A drawing press comprising a blank-holder or die-carrying slide and means for reciprocating the same with a dwell in its movement, said means comprising two rocking parts at the same side of the press, a rotary cam on the same side of the press as 80 said rocking parts, a reciprocating slide actuated by said cam, and means connecting said slide to said rocking parts for simultaneously rocking the same. 85

3. A drawing press comprising a punch slide, and means for driving said punch slide, comprising a crank-shaft and a driving wheel thereon, a blank-holder or die-carrying slide, and means for reciprocating the same with a dwell in its movement, said means comprising two rocking parts at the same side of the press, and means comprising a rotary cam on said wheel, on the same side of the press as said rocking parts, for simultaneously rocking said rocking parts. 90

4. A drawing press comprising a blank-holder or die-carrying slide, and means at each side of the press for reciprocating the same with a dwell in its movement, said means comprising at each side two rocking parts at the same side of the press, and means comprising a rotary cam on the same side of the press as said rocking parts for simultaneously rocking said rocking parts. 105

5. A drawing press comprising a blank-holder or die-carrying slide, and means at each side of the press for reciprocating the same with a dwell in its movement, said means comprising at each side two rocking parts at the same side of the press, a rotary cam on the same side of the press as said 110 rocking parts, a reciprocating slide actuated by said cam, and means connecting said slide to said rocking parts for simultaneously rocking the same. 120

6. A drawing press comprising a punch slide, and means for driving said punch slide, comprising a crank-shaft and driving wheels thereon at each side of the press, a blank-holder or die-carrying slide, and means at each side of the press for reciprocating the same with a dwell in its movement, said means comprising at each side two rocking parts at the same side of the press, and means comprising a rotary 125

cam on said wheel, on the same side of the press as said rocking parts, for simultaneously rocking said rocking parts.

7. A drawing press comprising side frames spaced a considerable distance apart, a blank-holder or die-carrying slide between said side frames, and means at each side of the press for reciprocating the same with a dwell in its movement, said means comprising at each side two rocking parts at the same side of the press, and means comprising a rotary cam on the same side of the press as said rocking parts for simultaneously rocking said rocking parts.

13 8. A drawing press comprising side frames spaced a considerable distance apart, a punch slide between said side frames, and means for driving said punch slide, comprising a crank shaft extending beyond said side frames, and driving wheels thereon at each side of the press beyond said side frames, a blank-holder or die-carrying slide between said side frames, and means at each side of the press for reciprocating the same with a dwell in its movement, said means comprising at each side two rocking parts at the same side of the press, and means comprising a rotary cam on the same side of the press as said rocking parts for simultaneously rocking said rocking parts.

9. A drawing press comprising side frames spaced a considerable distance apart, a punch slide between said side frames, and means for driving said punch slide, comprising a crank shaft extending beyond said side frames, and driving wheels thereon at each side of the press beyond said side frames, a blank-holder or die-carrying slide between said side frames, and means at each side of the press for reciprocating the same with a dwell in its movement, said means comprising at each side two rocking parts at the same side of the press, and means comprising a rotary cam on the same side of the press as said rocking parts for simultaneously rocking said rocking parts.

10. A drawing press comprising side frames spaced a considerable distance apart, a punch slide between said side frames, and means for driving said punch slide, comprising a crank shaft extending beyond said side frames, and driving wheels thereon at each side of the press beyond said side frames, a blank-holder or die-carrying slide between said side frames, and means at each side of the press for reciprocating the same with a dwell in its movement, said means comprising at each side two rocking parts at the same side of the press, and means comprising a rotary cam on the same side of the press as said rocking parts for simultaneously rocking said rocking parts, said cam being formed upon said wheel.

11. A drawing press comprising side frames spaced a considerable distance apart, a punch slide between said side frames, and means for driving said punch slide, comprising a crank shaft extending beyond said side frames, and driving wheels thereon at each side of the press beyond said side frames, a blank-holder or die-carrying slide between said side frames, and means at each side of the press for reciprocating the same with a dwell in its movement, said means comprising at each side two rocking parts at the same side of the press, a rotary cam on the same side of the press as said rocking parts, a reciprocating slide actuated by said cam, and means connecting said slide to said rocking parts for simultaneously rocking the same, said cam being formed upon the inner side of said wheel and said slide being located between said side frame and said wheel.

12. A drawing press comprising a blank-holder or die-carrying slide and means for reciprocating the same with a dwell in its movement, said means comprising two rocking parts at the same side of the press, a cam at the same side of the press as said rocking parts, a reciprocating slide actuated by said cam, and means connecting said slide to said rocking parts for simultaneously rocking the same, said cam being in the form of an eccentric circle, and said slide having thereon a block having an extended curved surface for bearing upon said cam.

13. A drawing press comprising a blank-holder or die-carrying slide and means for reciprocating the same with a dwell in its movement, said means comprising two rocking parts at the same side of the press, and means comprising a rotary cam on the same side of the press as said rocking parts for simultaneously rocking said rocking parts, and a second rocking part in serial relation to said first-named rocking parts between said cam and first-named rocking parts.

14. A drawing press comprising a blank-holder or die-carrying slide and means for reciprocating the same with a dwell in its movement, said means comprising two rocking parts at the same side of the press and a cam at the same side of the press as said rocking parts, a reciprocating slide actuated by said cam, and means connecting said slide to said rocking parts for simultaneously rocking the same, and a second rocking part in serial relation to said first-named rocking parts between said cam and first-named rocking parts.

15. A drawing press comprising a blank-holder or die-carrying slide and means for reciprocating the same with a dwell in its movement, said means comprising two rocking parts at the same side of the press, and means comprising a rotary cam on the same side of the press as said rocking parts for

simultaneously rocking said rock-shafts, a second rocking part in serial relation to said first-named rocking parts between said cam and said first-named rocking parts, and a 5 toggle connecting said first and second-named rocking parts.

16. A drawing press comprising a blank-holder or die-carrying slide and means for reciprocating the same with a dwell in its 10 movement, said means comprising two rocking parts at the same side of the press and a cam at the same side of the press as said rocking parts, a reciprocating slide actuated by said cam, and means 15 connecting said slide to said rocking parts for simultaneously rocking the same, a second rocking part in serial relation to said first-named rocking parts between said cam and said first-named rocking parts, and a 20 toggle connecting said first and second-named rocking parts.

17. A drawing press comprising a blank-holder or die-carrying slide and means for reciprocating the same with a dwell in its 25 movement, said means comprising two rocking parts at the same side of the press and a cam at the same side of the press as said rocking parts, a reciprocating slide actuated by said cam, and means connecting said 30 slide to said rocking parts for simultaneously rocking the same, said blank-holder or die-carrying slide moving in an opposite direction to said cam-actuated slide, whereby said slides counterbalance one another.

18. A drawing press comprising side frames spaced a considerable distance apart, a 35 punch slide between said side frames, and means for driving said punch slide, comprising a crank shaft extending beyond said side frames, and driving wheels thereon at each

side of the press beyond said side frames, a blank-holder or die-carrying slide between said side frames, and means at each side of the press for reciprocating the same with a dwell in its movement, said means 45 comprising two rocking parts at the same side of the press, and means comprising a rotary cam on the same side of the press as said rocking parts for simultaneously rocking said rocking parts, and a second rocking part in serial relation to said first-named rocking parts between said cam and said first-named rocking parts, and a toggle connecting 50 said first and second-named rocking parts.

19. A press comprising a frame, a blank-holder or die-carrying slide, four toggle connections between said frame and slide for reciprocating the latter, two at each side of the press, and means at each side of the 60 press for operating said toggles, comprising a cam and connections between said cam and the two toggles on the same side of the press therewith.

20. A press comprising a frame, a punch 65 slide, a blank-holder or die-carrying slide, four toggle connections between said frame and slide for reciprocating the latter, two at each side of the press, and means at each side of the press for operating said toggles, comprising a cam and connections between 70 said cam and the two toggles on the same side of the press therewith, said cam being independent of said punch slide, whereby it may operate to begin the lift of said blank-holder slide at about the same time the punch slide begins its return movement.

In witness whereof, I have hereunto signed my name.

OTTO S. BEYER.
